UNITED STATES PATENT OFFICE.

ALFRED D. ANTOINE, OF CHICAGO, AND CLARENCE C. TRAVIS, OF EVANSTON, ILLINOIS, ASSIGNORS TO ADVANCE MACHINE COMPANY, OF CHICAGO, ILLINOIS, A CORPORATION OF ILLINOIS.

CHECK-DETECTOR FOR CHECK-ACTUATED MACHINES.

1,372,666.

Specification of Letters Patent. Patented Mar. 29, 1921.

Application filed October 2, 1916. Serial No. 123,223.

To all whom it may concern:

Be it known that we, ALFRED D. ANTOINE and CLARENCE C. TRAVIS, citizens of the United States, residing, respectively, at 5 Chicago and Evanston, in the county of Cook and State of Illinois, have invented certain new and useful Improvements in Check-Detectors for Check-Actuated Machines, of which the following is a specification.

This invention relates to improvements in check detectors for check actuated machines which require the deposit of a check to render the same operative, and one of the 15 objects of the present invention is to provide an improved device of this character having means whereby the same may be operated when a check of a predetermined character is deposited therein and will be prevented 20 from operation by improper checks, disks, washers, etc., deposited therein, and which improper check will permit only a partial or incomplete operation of the mechanism, and at the same time the improper check 25 will be caught or arrested and prevented from reaching the coin actuated mechanism or other place where the presence of the coin is desired.

A further object is to provide improved 30 mechanism of this character embodying a casing having a coin outlet and means whereby the outlet will be closed and maintained closed until a proper check has been inserted in the mechanism, through the 35 medium of which check the outlet may be opened.

To the attainment of these ends and the accomplishment of other new and useful objects as will appear, the invention consists 40 in the features of novelty in substantially the construction, combination and arrangement of the several parts hereinafter more fully described and claimed and shown in the accompanying drawing, illustrating the 45 invention and in which—

Figure 1 is a rear elevation of an improved device of this character constructed in accordance with the principles of this invention.

50 Fig. 2 is a top plan view of the parts shown in Fig. 1.

Fig. 3 is a sectional view taken on the line 3—3, Fig. 6.

Fig. 4 is a sectional view taken on line 4—4, Fig. 6. 55

Fig. 5 is a sectional view on the line 5—5, Fig. 6.

Fig. 6 is a sectional view on line 6—6, Fig. 3.

Fig. 7 is a rear view of the front plate of 60 the casing with some of the parts removed.

Fig. 8 is an enlarged detail sectional view on the line 8—8, Fig. 6.

Fig. 9 is a view similar to Fig. 5 showing 65 the parts in a different position.

Fig. 10 is a view similar to Fig. 9 showing the parts in still another position.

Fig. 11 is an enlarged detail view of the parts in still another position.

Referring more particularly to the drawings and in the present form of the invention, the casing within which the mechanism is housed consists primarily of a front plate 15 and a rear plate 16, the front plate 15 being preferably of a size slightly larger 75 than the rear plate and being preferably provided with a circumferential flange within which the rear plate is arranged, the two plates when assembled constituting a housing having a check entrance opening 17, and a 80 discharge opening 18, the parts of the casing being secured together in any suitable manner, such as by means of suitable fastening devices.

Rotatably arranged within the casing thus 85 formed is a disk 19, and by the use of the term disk to be hereinafter employed in the specification and claims is to be understood to mean any suitable check carrying element.

The disk is provided with a check seat 20 90 opening through its periphery and is adapted to be rotated by means of a suitable handle 21, and the handle is preferably provided with a reduced extremity 22 having a threaded periphery and upon which is 95 threaded a nut 23 and this nut cooperates with a shoulder on the handle for securing the handle to the disk 19.

An elastic member 24 is provided in the casing, one end of which is anchored to a 100 suitable support and the other end is secured in any suitable manner to the disk 19 so that when the disk is rotated in one direction by the handle, a tension will be created upon the elastic member, and which tension 105 serves as a means for returning the disk to

its normal position, and in a position that the check seat in the disk will coincide with the check opening 17 in the casing.

Arranged adjacent the periphery of the disk is a catch 25 mounted by one extremity for pivotal movement and is provided with a hooked shaped extremity 26, adapted to coöperate with a shoulder 28 in the disk and which shoulder projects beyond the adjacent portion of the periphery of the disk. An elastic member 29 tends normally to move the extremity 26 of the catch 25 toward the periphery of the disk but it is held from engaging the periphery of the disk, in any suitable manner, such as by means of a shoulder 25^a. This catch serves the function of arresting the movement of the disk so that when a check of an improper character is placed within the check seat and is not of a proper diameter to swing the catch into an inoperative position when the disk is rotated, the extremity of the catch will be moved by the elastic member 29 into the path of movement of the shoulder 28 and thereby lock the disk against rotation to arrest the advancement of the check. Should, however, a check other than a proper check be deposited in the check seat and which check is of a size to engage the face 30 of the catch 25 sufficiently to shift the extremity of the catch, the check will be prevented from being discharged through the outlet opening 18, in a manner to be hereinafter described. A check of the proper character in the check seat 20 will engage the face 30 of the catch 25 and depress the catch and hold the catch in an inoperative position to permit the disk 19 to be rotated to its fullest extent to permit the check to be discharged from the check seat or out of the discharge opening 18 in the casing. A partition 31 is arranged within the casing and is provided with an opening 32 at its center through which the threaded nut or collar 23 of the handle 21 projects, and surrounding the opening is a flange 33 having an opening 34 therein to form a shoulder 35 (for a purpose to be hereinafter set forth), see particularly Fig. 4.

This partition 31 is provided with a slot or cutout portion 31^a that is adapted to receive a projection 37 carried by the disk 19, and the projection 37 coöperates with the extremity 38 of the slot 31^a which forms a stop for limiting the rotation of the disk 19 in one direction, when the catch 25 is in an inoperative position.

In order to lock the disk 19 against retrograde movement there is provided in the present form of the invention a reversible pawl 39 pivotally mounted as at 40 and controlled by an elastic element 41. This pawl is arranged so that its free extremity will be adjacent the periphery of the disk 19, and

the disk is provided with a series of peripheral notches 42, 42^a into which the pawl projects. Two recesses 43, 43^a are also provided in the periphery of the disk and between these recesses 43, 43^a the notches 42, 42^a are arranged. The notches 42 under predetermined conditions coöperate with the pawl 39 to lock the disk against movement in either direction, while the notches 42^a coöperate with the pawl to lock the disk against rotation in one direction only.

In normal position, the pawl 39 assumes the position shown in Fig. 5. Arranged adjacent the outlet opening 18 of the casing is a gravity controlled pivotally mounted member 44, the extremity 45 of which is normally in a position to receive the check, when the disk 19 is rotated to position the check seat 20 so that the check will drop therefrom to be passed out of the outlet opening 18. This member 44 is of such a weight that a check of the proper denomination and character which has been passed through the mechanism will overbalance the member and allow the check to pass out of the opening, being deflected through the opening by the projection of guide 46. Should a check which is lighter in weight than the proper check be passed through the mechanism, it will be manifest that the weighted portion of the element 44 will hold the check suspended and cause it to remain in the check seat so that when the disk 19 is again rotated to its normal position, the improper check will be brought back to a position where the operator can remove the same. The element 44 will not be tripped unless a check of the proper weight is deposited thereon.

In order to catch or hold washers and improper metallic disks within the check seat and prevent them from being delivered through the opening 18, a magnet 47 is provided adjacent the discharge opening 18 and in a position that the improper check in the check seat will pass thereover, when the disk 19 is rotated. Should therefore this improper check be of a sufficient weight to trip the gravity controlled element 44, it will be restrained from doing so by the magnet 47 to which the metallic disk will adhere and will also be retained in the check seat of the disk so that when the disk is returned to its normal position, the check may be removed from the check inlet opening 17.

In order to prevent a thin check from being passed between the disk and the stationary parts, the disk is preferably provided with lips or projections 48, 49 arranged adjacent the check seat 20 to project laterally beyond the side face of the disk. These projections are adapted to enter grooves or openings 50, 51 in the face of the parti-

tion 31 as shown more clearly in Fig. 6, and travel in these recesses as the disk is rotated.

A pivotally supported member 52 is arranged within the casing and is mounted for pivotal movement in any suitable manner preferably by being provided with a hollow hub 53 (see Figs. 3, 4 and 6), which is adapted to receive the nut or collar 23 on the end of the handle, and a portion of this hollow hub 53 is journaled in a suitable bearing 54 formed on the rear plate 16 of the casing.

The inner face of the member 52 abuts 15 the flange 33 so that a spring controlled dog 55 which is pivotally mounted upon the member 52 will coöperate with the shoulder 35 of the flange formed adjacent the opening 34, when the member 52 is 20 moved into the position shown in dotted lines in Fig. 4 in a manner to be described.

The member 52 is provided with laterally projecting portions 56 which form a check seat between the partition 31 and 25 the member 52, adapted to receive the check when the check carrier 19 is in the position shown in Figs. 10 and 11.

When the position of the member 52 is such that it will close the check outlet 30 opening 18 in the casing and when the check carrier 19 is in a position that the check will be discharged from the check seat, it will be delivered on to the portions 56 of the member 52.

35 A catch 57 is pivotally supported within the casing and is adapted to enter a notch 58 in the member 52 to lock it against swinging movement and to maintain the member 52 in a position to close the discharge opening in the casing.

This catch is preferably controlled by an elastic member 58 that tends to normally move the catch to a position to lock the member 52.

45 A portion of the catch projects between two of the projections 56 to such an elevation that when the check is delivered from the check seat 20 in the disk 19, on to the projections 56, it will also rest upon 50 the catch 57.

When the disk is moved into a position to discharge the check from the check seat 20 to the projections 56, the projection 37 on the disk will assume a position behind, 55 or to one side of the check (as shown in Fig. 11). As soon as the handle of the disk is released or the disk is moved backwardly, the projection 37 will contact with the edge of the check and force the check 60 downwardly upon the catch 57 to shift the latter and thereby release the member 52. A continued movement of the disk in the same backward direction will cause the member 52 with the check supported 65 thereby to be swung about its pivot in the

direction indicated by the arrows in Figs. 3 and 4, through the medium of the projection 37 engaging the edge of the check and shifting the check and member 52 until the dog 55 projects into the opening 34 of the 70 flange 33 to engage the shoulder 35 thereof. This will lock the member 52 in the position shown in dotted lines in Fig. 4 and the check will be maintained upon the projections 56 and also upon the projection 75 37 and the check seat 20 of the disk 19 will be moved to a position adjacent the opening 17 to receive another check. With the parts in this position (as shown in dotted lines in Fig. 4) the check will be main- 80 tained in the machine until the disk 19 is again rotated forwardly after the insertion of a new check. This movement of the disk 19 will then cause the projection 37 to move away from the projections 56 on 85 the member 52, and the latter will remain in the locked position shown in dotted lines in Fig. 4. At the same time the check which was held by the member 52 and the projections 56 will fall by gravity toward 90 and through the opening 32 in the partition 31 and also out of the discharge opening 18. This operation occurs just before the projection 37 engages the dog 59. Upon a further movement of the disk 19 in the same 95 direction and after the projection 37 engages the dog 59, the dog will be tripped to release the member 52, so that a still further forward movement of the disk 19 in the same direction will carry with it the 100 dog 59, causing the member 52 to swing about its pivot into the position shown in Figs. 1 and 3, thereby closing the discharge opening 18. The spring controlled catch 57 will then operate to enter the opening 58 105 in the member 52 and lock the latter against further movement until the insertion of a proper check.

It will thus be seen that unless a check of the proper character is deposited in the 110 check seat 20 of the disk 19, the member 52 will not be released and therefore the check will not be delivered through the outlet opening 18.

It is thought that the operation of this 115 device will be clearly understood from the above description but briefly stated it is as follows:

Assuming the parts to be in the positions shown in Fig. 5, the member 52 will be in 120 the position shown in Figs. 1 and 3 to close the outlet opening 18 of the casing. When a check of the proper character is deposited in the check seat, and the disk 19 is re- 125 volved, the check will first engage the surface 30 of the catch 25 to move the latter so that its extremity 26 will not engage the shoulder 28 of the disk. During this movement, the pawl 39 will assume the position shown in Fig. 9.

When the check seat 20 is in a position to discharge the check therefrom the check will fall upon the gravity controlled member 44 to trip the latter and the check will then be discharged on to the projections 56 of the member 52. The recess 43^a will then be in a position to receive the extremity of the pawl 39 so that when the disk is returned, the pawl 39 will be shifted so that it will ride over the notches 42 in the disk and permit the latter to be returned.

When the check seat 20 has reached a position to register with the inlet opening 17 of the casing, the recess 43 will then be in the position shown in Fig. 5 with respect to the pawl 39 to permit the pawl to shift its position so that the disk can be again rotated when another check is placed in the check seat. The notches 42^a are what might be termed "one way" notches or shoulders and coöperate with the pawl 39 to lock the disk against a forward rotation if it is attempted to rotate the disk again forwardly after it has discharged a check from the check seat and before the disk has been returned to its normal position, but will slide over these shoulders if the disk is rotated before a check is inserted in the check seat.

After the check is deposited upon the projections 56, the projection 37 of the disk will assume a position behind the check as shown in Fig. 11 so that the return movement of the disk will cause the projection to press upon the check to trip the catch 57 and release the member 52 and the member 52 will then be carried with the disk into the position shown in dotted lines in Fig. 4 to open the exit 18 and the member will be retained in this position by the dog 55.

When another check of a proper character is inserted and the same operation is repeated, the projection 37 will engage the dog 59 to swing it about its pivot and release the member 52 to permit it to again be moved in a position to close the opening 18 against the exit of an improper check, the projection 37 operating first to permit the check to fall before tripping the dog 59. Should an improper check, which is of a diameter smaller than a proper check, be inserted, the catch 25 will not be moved, and the extremity 26 will then engage the shoulder 28 of the disk and lock it against rotation, and the check will be returned to a position that it may be extracted by the operator.

Should a light weight check be inserted which would trip the catch 25 and permit the disk to be rotated to invert the check seat, the check will not be discharged therefrom as it will not be of sufficient weight to trip the gravity controlled member 44. Should a metallic disk such as an iron washer or the like be inserted in the check seat and is of such a size that it would trip

the catch 25, it will be retained in the check seat by the magnet 47 which will prevent it from being discharged upon the gravity controlled member 44 and when the disk is rotated in the opposite direction, the washer or metallic disk will then be returned to the inlet opening 17 so that it may be extracted by the operator. If desired a deflector 60 may be provided for deflecting or directing the check through the opening 18.

What is claimed as new is:—

1. A check detector embodying a casing having a check inlet and an outlet, a partition in the casing having an opening therethrough, a check carrier on one side of the partition, said carrier having a check seat adapted to be positioned to discharge the check through the opening in the partition, a shiftable element on the other side of the partition, a check support on the same side of the partition as the said shiftable element, and means connected with the check carrier and coöperating with the check on the said check support whereby the said element will be shifted.

2. A check detector embodying a casing having a check inlet and an outlet, a partition in the casing having an opening therethrough, a check carrier on one side of the partition, said carrier having a check seat adapted to be positioned to discharge the check through the opening in the partition, a shiftable element on the other side of the partition, and means controlled by the check carrier whereby the said element will be shifted by the check, the said means embodying a projection on the carrier extending through the partition and adapted to engage and shift the check.

3. A check detector embodying a casing having a check inlet and an outlet, a partition in the casing having an opening therethrough, a check carrier on one side of the partition for moving the check through the casing and delivering the same through the partition, a shiftable controlling element on the side of the partition opposite to the side on which the check carrier is located, said element embodying a check support on the same side of the partition as said element and adapted to receive the check as it is discharged from the carrier and through the partition, and means connected with the check carrier and adapted to engage and shift the check from the said support, said support operating to actuate the said controlling element.

4. A check detector embodying a casing having a check inlet and an outlet, a partition in the casing having an opening therethrough, a check carrier on one side of the partition for moving the check through the casing and delivering the same through the partition, a shiftable controlling element on the side of the partition opposite to the side

on which the check carrier is located, said element embodying a check support on the same side of the partition as said element and adapted to receive the check as it is discharged from the carrier through the partition, and means connected with the check carrier and adapted to engage and shift the check from the said support, said support operating to actuate the said controlling element, the said means embodying a projection connected with the check carrier and extending through the said partition to engage the edge of the check.

5. A check detector embodying a casing having a check inlet and an outlet, a partition in the casing having an opening therethrough, a check carrier on one side of the partition for moving the check through the casing and delivering the same through the 20 partition, a shiftable controlling element on the side of the partition opposite to the side on which the check carrier is located, said element embodying a check support on the same side of the partition as said element and adapted to receive the check as it is discharged from the carrier and through the partition, means connected with the check carrier, and adapted to engage and shift the check from the said support, said 25 support operating to actuate the said controlling element, and a yieldable element adjacent the path of movement of the check for maintaining an improper check against delivery from the check carrier.

30 6. A check detector embodying a casing having a check inlet and an outlet, a partition in the casing having an opening therethrough, a check carrier on one side of the partition for moving the check through the casing and delivering the same through the 35 partition, a shiftable controlling element on the side of the partition opposite to the side on which the check carrier is located, said element embodying a check support on the same side of the partition as said element and adapted to receive the check as it is discharged from the carrier and through the partition, means connected with the check carrier and adapted to engage and 40 shift the check from the said support, said support operating to actuate the said controlling element, and provisions embodying mechanism whereby any check of an 45 improper weight will be retained against delivery to the said support.

50 7. A check detector embodying a casing, a check carrier rotatable therein, said carrier having a check seat, a support for receiving the check, and means connected with the said carrier and adapted to operate upon the check after the latter has been discharged from the check seat, the last recited means embodying a lateral projection on the check carrier adapted to engage the edge of the 55 check to advance the check.

8. A check detector embodying a casing having a check inlet and a check outlet, a check carrier operable in the casing, means for closing the said outlet against the passage of an improper check therethrough, and mechanism which, in the presence of a proper check in the carrier will automatically shift the last recited means to open the outlet.

9. A check detector embodying a casing having a check inlet and a check outlet, a check carrier operable in the casing, means for closing the said outlet against the passage of an improper check therethrough, mechanism which, in the presence of a proper check in the carrier will automatically shift the last recited means to open the outlet, means for maintaining the first recited means in its shifted position, and means for automatically releasing the first 85 recited means.

10. A check detector embodying a casing having a check inlet and a check outlet, a check carrier operable in the casing, means for closing the said outlet against the passage of an improper check therethrough, mechanism which, in the presence of a proper check in the carrier will automatically shift the last recited means to open the outlet, means for maintaining the first recited means in the shifted position, and means connected with the check carrier for automatically rendering the said outlet closing means active to close said outlet.

11. A check detector embodying a casing having a check inlet and a check outlet, a check carrier arranged in the casing, a closure for said outlet, a check seat connected with the closure and adapted to receive the check from the carrier, and means connected with the check carrier and operable upon the check in the said seat for shifting the said closure to open said outlet.

12. A check detector embodying a casing having a check inlet and a check outlet, a check carrier arranged in the casing, a closure for said outlet, a check seat connected with the closure and adapted to receive the check from the carrier, means operable only by a check of a predetermined character for controlling the delivery of the check to the said seat, and means rendered active by a check in said seat for shifting said closure to open said outlet.

13. A check detector embodying a casing having a check inlet and a check outlet, a check carrier arranged in the casing, a closure for said outlet, a check seat connected with the closure and adapted to receive the check from the carrier, means operable only by a check of predetermined character for controlling the delivery of the check to the said seat, means rendered active by a check in said seat for shifting said closure to open said outlet, means for locking the said 125

closure in its shifted position, and means for automatically releasing the said closure.

14. A check detector embodying a casing having a check inlet and a check outlet, a check carrier arranged in the casing, a closure for said outlet, a check seat connected with the closure and adapted to receive the check from the carrier, means operable only by a check of a predetermined character for controlling the delivery of the check to the said seat, and means connected with the carrier and coöperating with the check on said seat for shifting the said closure to open said outlet.

15. 15. A check detector embodying a casing having a check inlet and a check outlet, a check carrier arranged in the casing, a closure for said outlet, a check seat connected with the closure and adapted to receive the check from the carrier, means operable only by a check of a predetermined character for controlling the delivery of the check to the said seat, means connected with the carrier and coöperating with the check in said seat for shifting the said closure to open the outlet and mechanism for locking the closure in such position, the last recited means also operating to release the closure to render the latter active to close said outlet.

30 16. A check detector embodying a casing having a check inlet and a check outlet, a check carrier arranged in the casing, a closure for said outlet, a check seat connected with the closure and adapted to receive the check from the carrier, means operable only by a check of a predetermined character for controlling the delivery of the check to the said seat, means connected with the carrier and coöperating with the check in said seat for shifting the closure to open the outlet, and a catch for maintaining the closure in its last said position, the last recited means being also adapted to render the catch inactive to release the closure.

45 17. A check detector embodying a casing having a check inlet and a check outlet, a check carrier in the casing, a closure for the outlet, a check receiver connected with the closure and adapted to receive the check from the carrier, means whereby only checks of a predetermined character will be delivered from said carrier, means for locking the said closure in position to close the opening, and means rendered active by the movement of the said carrier and operable upon a check in said seat to first release the said closure and then shift the latter to open said outlet.

60 18. A check detector embodying a casing having a check inlet and a check outlet, a check carrier in the casing, a closure for the outlet, a check receiver connected with the closure and adapted to receive the check from the carrier, means whereby only checks of a predetermined character will be de-

livered from said carrier, means for locking the said closure in position to close the opening, means rendered active by the movement of the said carrier and operable upon a check in said seat to first release the said closure and then shift the latter to open said outlet, and mechanism for retaining the closure in its last recited position, the last recited means also operating to release the closure to close the said outlet. 75

19. A check detector embodying a casing having a check inlet and a check outlet, a check carrier in the casing, a closure for the outlet, a check receiver connected with the closure and adapted to receive the check from the carrier, means whereby only checks of a predetermined character will be delivered from said carrier, means for locking the said closure in position to close the opening, a projection connected with the carrier and adapted to operate upon the check in the seat to release and shift the closure to open said outlet, and means embodying a catch for retaining the closure in the last recited position, said projection being also adapted to render the catch inactive to release the closure. 80

20. A check detector embodying a casing having a check inlet and a check outlet, a check carrier in the casing, a closure for the outlet, a check receiver connected with the closure and adapted to receive the check from the carrier, means whereby only checks of a predetermined character will be delivered from said carrier, means for locking the said closure in position to close the opening, a projection connected with the carrier and adapted to operate upon the check in the seat to release and shift the closure to open said outlet, means embodying a catch for retaining the closure in the last recited position, said projection being also adapted to render the catch inactive to release the closure, and provisions whereby said projection will limit the movement of said 100 carrier. 105

21. A check detector embodying a casing having an outlet, a check carrier for advancing the check, a closure for the outlet, said closure having a check seat and adapted to receive the check from the carrier, a catch for locking the closure in a closing position, a portion of the catch projecting into the check seat to be engaged by the check, a projection on the carrier adapted to engage the 115 check to shift the catch to unlock the closure and also for shifting the closure to open the outlet, and means embodying a catch for locking the closure in its last recited position, the said last recited catch adapted to 120 be engaged and shifted by the said projection to release the closure. 125

22. A check detector embodying a casing having an outlet, a check carrier for advancing the check, a closure for the outlet, said 130

closure having a check seat and adapted to receive the check from the carrier, a catch for locking the closure in a closing position, a portion of the catch projecting into the 5 check seat to be engaged by the check, a projection on the carrier adapted to engage the check to shift the catch to unlock the closure and also for shifting the closure to open the outlet, means embodying a catch 10 for locking the closure in its last recited position, the last recited catch adapted to be engaged and shifted by the said projection to release the closure, and means for permitting only a check of a predetermined 15 character to be delivered from the carrier to the said seat.

23. A check detector embodying a casing having an outlet, a check carrier for advancing the check, a closure for the outlet, said 20 closure having a check seat and adapted to receive the check from the carrier, a catch for locking the closure in a closing position, a portion of the catch projecting into the check seat to be engaged by the check, a 25 projection on the carrier adapted to engage the check to shift the catch to unlock the closure and also for shifting the closure to open the outlet, means embodying a catch for locking the closure in its last recited position, the last recited catch adapted to be 30 engaged and shifted by the said projection to release the closure, and provisions for intercepting the delivery of any improper check from the carrier to the said check seat.

35. 24. A check detector embodying a casing having an outlet, a check carrier for advancing the check, a closure for the outlet, said closure having a check seat and adapted to receive the check from the carrier, a catch 40 for locking the closure in a closing position, a portion of the catch projecting into the check seat to be engaged by the check, a projection on the carrier adapted to engage the check to shift the catch to unlock the 45 closure and also for shifting the closure to open the outlet, means embodying a catch for locking the closure in its last recited position, the last recited catch adapted to be 50 engaged and shifted by the said projection to release the closure, and provisions for intercepting the delivery of any improper check from the carrier to the said check seat, the said provisions embodying a gravity controlled member shiftable by a proper 55 check.

25. A check detector embodying a check 60 passage, a check carrier having a check seat for advancing the check through the passage, a catch for arresting the movement of the carrier, said catch being adapted to be rendered inactive by the check in the seat, said passage having an outlet, and provisions embodying mechanisms whereby any check of an improper weight will be 65 retained in the check seat.

26. A check detector embodying a casing having a check inlet and an outlet, a partition in the casing having an opening therethrough, a check carrier on one side of the partition, said carrier having a check seat 70 adapted to be brought into register with the opening in the partition to discharge the check therethrough, a projection on the carrier extending through the partition, and a pivoted member on the other side of the 75 partition and operating to close the casing outlet, said member having a check seat to receive the check from the carrier, said projection adapted to engage the check on the last said seat to shift the said member to 80 open said outlet.

27. A check detector embodying a casing having a check inlet and an outlet, a partition in the casing having an opening therethrough, a check carrier on one side of the 85 partition, said carrier having a check seat adapted to be brought into register with the opening in the partition to discharge the check therethrough, a projection on the carrier extending through the partition, a 90 pivoted member on the other side of the partition and operating to close the casing outlet, said member having a check seat to receive the check from the carrier, said projection adapted to engage the check on the 95 last said seat to shift the said member to open said outlet, and a catch for locking the member to close the opening, said catch being adapted to be engaged and tripped by the check to release the member. 100

28. A check detector embodying a casing having a check inlet and an outlet, a partition in the casing having an opening therethrough, a check carrier on one side of the partition, said carrier having a check seat 105 adapted to be brought into register with the opening in the partition to discharge the check therethrough, a projection on the carrier extending through the partition, a pivoted member on the other side of the 110 partition and operating to close the casing outlet, said member having a check seat to receive the check from the carrier, said projection adapted to engage the check on the last said seat to shift the said member to open 115 said outlet, and mechanism for locking the member in its last said position, said mechanism embodying a catch adapted to be engaged and shifted by said projection to release the member. 120

29. A check detector embodying a casing having a check inlet and an outlet, a partition in the casing having an opening therethrough, a check carrier on one side of the partition, said carrier having a check seat 125 adapted to be brought into register with the opening in the partition to discharge the check therethrough, a projection on the carrier extending through the partition, a pivoted member on the other side of the 130

- partition and operating to close the casing outlet, said member having a check seat to receive the check from the carrier, said projection adapted to engage the check on the 5 last said seat to shift the said member to open said outlet, and provisions whereby only checks of a predetermined character will be delivered from the carrier to the check seat on the said member.
- 10 30. A check detector embodying a casing having a check inlet and an outlet, a partition in the casing having an opening therethrough, a check carrier on one side of the partition, said carrier having a check seat 15 adapted to be brought into register with the opening in the partition to discharge the check therethrough, a projection on the carrier extending through the partition, a pivoted member on the other side of the partition and operating to close the casing outlet, said member having a check seat to receive the check from the carrier, said projection adapted to engage the check on the 20 last said seat to shift the said member to open said outlet, and a gravity controlled pivoted member operable only by a check of a predetermined character for retaining improper checks in the check seat of the said carrier.
- 25 31. A check detector embodying a casing having a check inlet and an outlet, a partition in the casing having an opening there-

through, a check carrier on one side of the partition, said carrier having a check seat adapted to be positioned to discharge the 35 check through the opening in the partition, a shiftable element on the other side of the partition and operating to close the casing outlet, and means controlled by the check carrier for shifting the said element to open 40 said outlet.

32. A check detector embodying a casing having a check inlet and an outlet, a partition in the casing having an opening therethrough, a check carrier on one side of the 45 partition, said carrier having a check seat adapted to be positioned to discharge the check through the opening in the partition, and a shiftable element on the other side of the partition and operating to close the casing outlet, said element being responsive in its shifting movement to the operation of the check carrier through the medium of a check positioned by the carrier.

In testimony whereof we have signed our 55 names to this specification, in the presence of two subscribing witnesses, on this 23rd day of September, A. D. 1916.

ALFRED D. ANTOINE.
CLARENCE C. TRAVIS.
